[57] ABSTRACT

The specification discloses a circuit for starting a plurality of fluorescent lamps. The ordinary fluorescent lamp requires a heavy inductance, usually referred to as a ballast, for starting the lamps. The ballast is heavy and expensive. A lightweight resistance could be substituted for the ballast, if a simple means could be found to start the lamp. The present invention uses a single transformer to supply a higher voltage of, for example, 180 volts, for starting and a switching arrangement for switching the transformer from lamp to lamp. After the lamps are started they are switched onto a standard line voltage of 120 volts, for example. Thus, a single transformer is required to light a number of lamps.

FLUORESCENT LIGHTING CIRCUIT

DESCRIPTION OF PRIOR ART

The iron core ballast, as it is known today, is used to start the fluorescent tube/tubes and then switched out of the circuit and the tube-tubes function on line voltage along.

OBJECTS OF THE INVENTION

An object of this invention is to provide an improvement in fluorescent circuits and, more particularly, an improved lighting circuit for fluorescent lamps.

Another object of the invention is to provide a simple, inexpensive resistor circuit for 48 inch tubes or longer.

Another object of the invention is to provide a single starting circuit for fluorescent lamps.

Yet another object of the invention is to provide a functioning fluorescent circuit which is light in weight, low in manufacturing cost, and inexpensive to maintain.

DESCRIPTION OF THE DRAWINGS

FIG. 1 shows a switch-out ballast circuit;

FIG. 2 shows a tube and a plug-in removable unit according to the invention; and

FIG. 3 is a solid state type starter circuit.

DETAILED DESCRIPTION OF THE DRAWINGS

In the drawings, referring to the embodiment shown in FIG. 1, three fluorescent tubes 10, 11, and 12 are shown, each having a starter 13, 14, and 15, respectively, and each having a ballast resistor 16, 17, and 18, respectively, connected in series therewith.

The source of power made up of lines 130 and 131 may be connected, for example, to a 120 volt A. C. line and the A. C. line may be connected to the fluorescent lights through a switch 25 having contacts SW1, SW2, and SW3, respectively.

The line switch 25 connects the power supply from lines 130 and 131 to the transformer 22. The auto transformer 22 will put out approximately 180 volts for starting the tubes. The autotransformer output is connected to the tubes selectively through capacitor 20 and 21 by the switch 24 by the selected contacts 3, 4, 3', 4', 3'', and 4'', respectively. When the switch contacts are switched from contacts 3, 4 to contacts 3', 4', for example, the starting voltage will be removed from contacts 3, 4 and applied to contacts 3' and 4'. Thus, the fluorescent

tubes will be started by the higher voltage and will operate on the line voltage.

Referring to the embodiment of the invention shown in FIG. 2, the fluorescent tube 110 has a starter 113 supported in the unit 140. The unit starter is plugged into the other wires 1, 2, 3, and 4 by a suitable jack arrangement and is likewise connected to the power lines 130 and 131 by the suitable jack arrangement shown.

A fuse 123 protects the line from malfunction of the circuit. 10 An auto transformer 122 has its output connected through condensers 120 and 121 into parallel connection with the lines 130 and 131. Thus, the output of the auto transformer 122 and the starter 113 can be switched intermittently and selectively to a plurality of tubes 110 so that all of the tubes can be 15 started from the same power source.

Now with reference to FIG. 3 which shows a portable battery operated circuit for switching the ballast out of the circuit, it shows a starter 221 connected in terminals 1 and 2 which will be connected to the filaments of fluorescent tubes 20 and a transformer primary 214 with secondaries 215 connected in push-pull arrangement to transistors 216 and 217. The output of the transistors is fed through the resistors 219 and 220 back into the windings 221 and 222. Thus, the output of batteries B1 and B2 puts out a voltage which is stepped up 25 through the windings 215, 221, and 222 through winding 214 and into auto transformer 233. This output is connected to condensers 234 and 235 to the terminals 3 and 4 which will be connected to the terminals of a fluorescent light intermittently to start it.

The foregoing specification sets forth the invention in its preferred practical forms but the structure shown is capable of modification within a range of equivalents without departing from the invention which is to be understood is broadly novel as is commensurate with the appended claims.

The embodiments of the invention in which an exclusive property or privilege is claimed are defined as follows:

1. A starting circuit for a plurality of fluorescent lamps comprising:
first switch means for connecting said plurality of lamps to a source of power,
second switch means including an auto transformer and capacitor means for sequentially applying a starting voltage from said source of power to each of said plurality of lamps, said capacitor means connected between said transformer and said lamps.
